UTILITY CAP OR THE LIKE

Therese Gilman, New York, N. Y.

Application November 16, 1949, Serial No. 6,075

Term of patent 7 years

(Cl. D3—13)

To all whom it may concern:

Be it known that I, Therese Gilman, a citizen of the United States of America, residing in the city of New York, county of New York, State of New York, have invented a new, original, and ornamental Design for a Utility Cap or the like, of which the following is a specification, reference being had to the accompanying drawings forming a part thereof, wherein:

Fig. 1 is a front perspective view of a utility cap or the like showing my new design.

Fig. 2 is a rear elevational view thereof.

Fig. 3 is a side elevational view as it appears in wearing position.

I claim:

The ornamental design for a utility cap or the like, substantially as shown and described.

THERÈSE GILMAN,
